UNITED STATES PATENT OFFICE.

THOMAS J. WOODCOCK, OF PHILADELPHIA, PENNSYLVANIA.

KNIT FABRIC.

SPECIFICATION forming part of Letters Patent No. 577,702, dated February 23, 1897.

Application filed January 14, 1896. Serial No. 575,434. (Specimens.)

To all whom it may concern:

Be it known that I, THOMAS J. WOODCOCK, of Philadelphia, (Germantown,) in the county of Philadelphia and State of Pennsylvania, 5 have invented a new and Improved Knit Fabric, of which the following is a full, clear, and exact description.

My invention relates to knitted fabrics, and the object of the invention is to provide a 10 knitted fabric especially designed for the body portion of hammocks, but which may be also used wherever a particularly strong knitted material is required.

A further object of the invention is to produce a knitted fabric in which the warp will 15 be crossed by chain-strokes in such a manner as to firmly bind the warp and to produce a material which will have the least possible tendency to ravel if punctured or torn.

20 The invention consists in the novel combination of the threads comprising a knitted fabric, as will be hereinafter fully set forth, and pointed out in the claims.

Reference is to be had to the accompanying 25 drawing, forming a part of this specification, in which the figure is a plan view of a piece of the fabric, illustrating the manner in which the warp-threads are connected and crossed by the chain-threads, the threads being ex- 30 aggerated and widely spaced, so that their relation to each other may be more clearly traced.

In the construction of the fabric two sets 35 of warp-threads A A' are employed, the said threads being arranged in serpentine form, one in rear of the other, with the bights of the two sets turned in opposite directions and overlapping one another, so that the overlapping portions thereof form a series of rings a, 40 as shown. The straight portions 10 of the warp-threads lie in parallel planes, and the bent or return portions 11 of each set of warp-threads are opposite to and in a measure extend within the open spaces between the 45 straight portions of the next or adjoining thread of its set.

The fabric is produced upon a warp-knitting machine having, in addition to the usual guides for the knitting or chain threads B, 50 supplemental guides for the warp-threads A A', the latter being moved back and forth a space of two needles after the completion of

each course of loops upon the needles of threads B, the result being that the loops of threads B inclose the bights or other portions 55 of threads A A' in the manner shown.

Each thread B is continuous and forms a chain of stitches or loops, which consists of loops 12 and connecting portions 13, the loop proper and the connecting portion lying upon 60 opposite sides of and inclosing and connecting the bights of the adjacent warp-threads of each set. In this manner the chain-threads serve to connect the warp-threads securely together and constitute a body or filling for 65 the fabric of superior character and one through which an object of comparatively large diameter may be passed without tearing the threads, as the threads will open for the passage of the object, and if a thread should 70 become broken the opening made thereby will not be so liable to increase in size as it would in the ordinary knit fabric.

Having thus described my invention, I claim and desire to secure by Letters Patent—

1. A knit fabric composed of warp and knitting threads, the warp-threads being arranged in two sets one in rear of the other, the threads being in serpentine lines with the bights of 80 the two sets turned in opposite directions and overlapping as shown, bights of adjacent threads of one set of warps being connected by one set of the knitting-threads and bights of adjacent threads of the other set of 85 warps being connected by the other knitting-threads, substantially as described.

2. A knitted fabric composed of warp-threads arranged one in rear of the other, the threads of each set being in serpentine lines 90 with the bent or return portion of one thread opposite to and extending a short distance between the straight portions of the adjacent thread, the threads of the two sets being turned in opposite directions and overlapping 95 one another, and knitting-threads alternately connecting two bent or return portions of one set of warp-threads with a straight portion of the other set of warp-threads, substantially as herein shown and described.

THOMAS J. WOODCOCK.
